UNITED STATES PATENT OFFICE.

EDWARD M. BURNEY, OF CHICAGO, ILLINOIS.

JACK-SCREW.

979,424.

Specification of Letters Patent. Patented Dec. 27, 1910.

Application filed June 1, 1909. Serial No. 499,382.

To all whom it may concern:

Be it known that I, EDWARD M. BURNEY, a citizen of the United States, residing at Chicago, county of Cook, and State of Illinois, have invented certain new and useful Improvements in Jack-Screws, of which the following is a specification.

My invention relates to jack screws, and the object of my invention is to provide an improved jack screw wherein the screw and the cap pivot shall be securely fixed to the head, to the end that the same shall be strong and durable and without liability of separation of the parts when in use.

15 A further object of my invention is to provide a device of the class mentioned which shall be of simple construction and which may be manufactured at low cost.

Other objects will appear hereinafter.

20 My invention will be more readily understood by reference to the accompanying drawings forming a part of this specification and in which—

Figure 1 is an elevation of a jack screw embodying my invention in its preferred form, Fig. 2 is a vertical sectional view of the same, the screw and cap pivot being shown in elevation, and Fig. 3 is a detail transverse section taken on substantially the 30 line $x-x$ of Fig. 2.

Referring now to the drawings 1 indicates a screw having the usual thread 2. I extend the thread of the screw almost to the upper end thereof and terminate the 35 same with a shoulder 3, the purpose of which will appear hereinafter.

4 indicates a cylindrical cap pivot having a peripheral annular groove 5 formed therein adjacent its lower end, and 6 the head 40 of the screw. The head 6 is cast on the

screw and pivot, the metal thereof extending several threads downwardly on the screw and above the groove 5 of the cap pivot. By constructing the screw in this manner separation of the several parts is 45 prevented as the metal of the head enters between the threads 2 and into the groove 5. The shoulder 3 at the upper end of the thread is also embedded in the metal of the head and prevents relative turning of the 50 head and screw when the device is in use. The head is provided with radial lever bar openings 7 which are cored therein when the head is molded, and extend through the head between the ends of the screw and the 55 pivot 4.

Having described my invention what I claim as new and desire to secure by Letters Patent is:

1. A jack screw comprising a screw having a thread extending almost to its upper end and terminating in a shoulder, and a head cast upon the upper end of said screw, extending several threads downwardly thereon, and provided with lever bar openings, 65 substantially as described.

2. In a jack screw a head and a cylindrical cap pivot having a peripheral annular groove adjacent its lower end, said lower end including said groove being embedded 70 within said head when the latter is cast, substantially as described.

In testimony whereof I have signed my name to this specification in the presence of two subscribing witnesses.

EDWARD M. BURNEY.
